CLAIM

The ornamental design for a display screen or portion thereof with graphical user interface as shown and described.

DESCRIPTION

The file of this patent contains at least one drawing/photograph executed in color. Copies of this patent with color drawings(s)/photograph(s) will be provided to the Office upon request and payment of the necessary fee.

FIG. 1 is a front view of a display screen or portion thereof with graphical user interface showing a first embodiment of the claimed design in color;

FIG. 2 is a front view of a second embodiment thereof;

FIG. 3 is a front view of a third embodiment thereof;

FIG. 4 is a front view of a display screen or portion thereof with graphical user interface showing a fourth embodiment of the claimed design without color;

FIG. 5 is a front view of a fifth embodiment thereof; and, FIG. 6 is a front view of a sixth embodiment thereof.

The dot-dash lines represent the display screen or portion thereof and form no part of the claimed design. The gray dashed lines form part of the claimed design.
